ROBERT KAUCH AND CHARLES L. PAULUS, OF DAYTON, OHIO.

SELF-LOCKING RUDDER BAR.

Application filed May 11, 1923. Serial No. 638,297.

To all whom it may concern:

Be it known that we, ROBERT KAUCH and CHARLES LEIGH PAULUS, citizens of the United States, residing at Dayton, in the county of Montgomery and State of Ohio, have invented certain new and useful Improvements in Self-Locking Rudder Bars, of which the following is a specification.

This device relates to controlling devices more particularly constructed for use in connection with airplanes or like machines wherein the main controlling member used for the operation of the vertical rudder is arranged to be actuated with the aid of a rudder bar by the pilot's feet.

The object of this invention is to provide a rudder bar which will provide means for locking the rudder in a fixed position in order that the rudder, thus set in proper position to counteract propeller torque and cross winds will be a means for maintaining correct flight of the aircraft without the aid of constant appliance by the pilot of his feet on the rudder bar to keep the rudder in the desired position.

With the foregoing and other objects in view, which will appear as the description proceeds, the invention consists in the combination of parts and details of construction hereinafter described and claimed, it being understood that various changes in the precise embodiment hereinafter described may be made without departing from the spirit of the invention illustrated in the attached drawings in which:

Figure 1 is a front elevation, partly in section of one-half of the rudder bar, showing the manner in which it is mounted and also the locking attachments.

Figure 2 is a top plan view of one-half of the rudder bar assembly.

Figure 3 is an end view in elevation of the locking pedal of the rudder bar, showing an adjusted position in dotted lines.

Figure 4 is a diagrammatical view of the cam actuating against the movable friction clutch plates, the lobes of the cam being in such a position as to force the plates in opposite direction and thus release them from their frictional engagement with the stationary plate on the rudder bar.

Figure 5 is a view of the same parts as Figure 4, showing, however, the cam in such a position as to allow the movable clutch plates to be closer together and thus fric-

tionally engage the stationary plate on the rudder bar.

Referring more particularly to the drawings it will be seen that a rudder bar 1 is of conventional design and so mounted as to rotate on a fulcrum stud 2, which is mounted on a suitable base 3, the base 3 being approximately cylindrical in form and having mounted on its upper surface, by use of rivets 4, a fixed plate 5.

A lower friction clutch plate 6 and an upper plate 7 are provided with lugs 6' and 7' to facilitate the mounting of a spring 9 which is maintained in position on a stud 10 by a washer 11 and cotter pin 12. The function of the spring is to provide pressure upon the stationary plate 5 which will prevent rotation of the rudder bar 1. Cams 13 are fixed to a shaft 8 by which arrangement they may be rotated by actuation of the foot pedals 14. The foot pedals 14 are provided with levers 15 which have integral collar bearing members 16 to be mounted on the shaft 8 and keyed thereto by pins 16'. Shaft 8 is further supported by bearing members 17 and 22, the shaft being mounted free to rotate therein, the bearing 17 being maintained in place by means of the bolts 18.

Figure 3 shows, in dotted lines, the normal position assumed as soon as pressure is removed from the pedal 14. It will be observed that the 30 degrees movement is limited by stops 22'.

Figure 5 shows in detail the cam 13 as it is normally carried with the rudder bar in locked position, while Figure 4 shows the cam rotated through an arc of 30 degrees. This rotation spreads the surfaces of the upper and lower friction clutch plates, 7 and 6, and thereby releases them from frictional engagement with the stationary plate 5. While only one side of the rudder bar is shown in the drawings it will be understood that the other side is identical in design and operation. Thus as the shaft 8 extends throughout the entire length of the rudder bar, pressure on either foot pedal 14 will release the rudder bar for normal operation.

Referring again to Figure 2, it will be noted that the spring stud 10 is mounted off center to permit the full extension of the shaft 8. Any tendency to rotate the movable friction clutch plates 6 and 7 about

the axis of the shaft 8 is prevented as one spring assembly is mounted on one side of shaft 8 and the other spring assembly on the opposite side of the rudder bar is mounted on the other side of the shaft 8.

The bracket 19 is shown merely to designate a means for attaching the rudder bar to a cable 20. This cable in turn extends to the conventional vertical rudder control 10 surface in the usual manner.

Having thus described our invention we claim:—

1. In a controlling device for aircraft, the combination of a main controlling member, 15 a pair of actuating pedals movably connected to said member and through the medium of which said member is moved, a retaining member and clutch members operatively connected to said pedals and arranged to 20 cooperate with the retaining member, of each of said clutch members being released by relative movement of its respective pedals with respect to the controlling member incident to the actuation of said pedal and the 25 controlling member, each of said clutch members consisting of an upper and lower movable friction clutch plate adapted to frictionally engage said retaining member on either side thereof accordingly.
2. In a controlling device for aircraft, the combination of a main controlling member, 30 a pair of actuating pedals movably connected to said member and through the medium of which said member is moved, a retaining member, and clutch members operatively connected to said pedals and arranged to 35 cooperate with the retaining member, each of said clutches consisting of an upper and lower movable friction clutch plate adapted 40 to normally frictionally engage said retaining member on either side thereof accordingly, means operated by said pedals for disengaging said clutch plates from said retaining member, said last named means consisting of double lobed cams arranged 45 between said clutch plates and mounted on a rotary shaft operated by said pedals.
3. In a controlling device for aircraft, the combination of a main controlling member, 50 a pair of actuating pedals movably connected to said member and through the medium of which said member is moved, a retaining

member, and clutch members operatively connected to said pedals and arranged to co-operate with the retaining member, each of 55 said clutch members consisting of an upper and lower movable friction clutch plate adapted to normally frictionally engage said retaining member on either side thereof accordingly, means operated by said pedals 60 for disengaging said clutch members from said retaining member, said last named means consisting of double lobed cams arranged between said clutch plates and mounted on a rotary shaft operated by said 65 pedals, and stop means for limiting the movement of said pedals.

4. In a controlling device for aircraft, the combination of a main controlling member, 70 a pair of actuating pedals movably connected to said member and through the medium of which said member is moved, a retaining member, and clutch members operatively connected to said pedals and arranged to normally non-positively engage said retaining member and prevent rotation thereof, 75 each of said clutch members being released by relative movement of said pedals with respect to the controlling member incident to the actuation of said pedals and the controlling member, said pedals being mounted on a shaft, cams mounted on said shaft and adapted to actuate said clutches upon the simultaneous actuation of said pedals and rotation of said shaft.

5. In a controlling device for aircraft, a rudder bar, a retaining member, clutch faces for engagement with the retaining member, 80 said clutch faces each provided with an extension and means between said extensions 90 for controlling the movement of said clutch faces relative to said retaining member.

6. In a controlling device for aircraft, a rudder bar, a retaining member, clutch faces for engagement with said retaining member, 95 said clutch faces each having extensions thereon, cams positioned between said extensions and means for actuating said cams to control the movement of said clutch faces relative to said retaining member. 100

In testimony whereof we affix our signatures.

ROBERT KAUCH.
CHARLES L. PAULUS.
